UNITED STATES PATENT OFFICE.

JOSEPH E. RINGEL, OF WALLA WALLA, WASHINGTON.

JAR LIFTER.

Application filed August 8, 1921, Serial No. 490,531. Renewed November 21, 1922.

To all whom it may concern:

Be it known that I, JOSEPH E. RINGEL, a citizen of the United States, residing at Walla Walla, in the county of Walla Walla 5 and State of Washington, have invented certain new and useful Improvements in Jar Lifters, of which the following is a specification.

This invention relates to improvements 10 in jar lifters in which a hinged circular band carries the parts which go to make up the device and in which a free opening up into the handle is provided to receive the maximum height jar.

15 One object of the invention is to provide a jar lifter that is adaptable to various household uses but more particularly that of lifting jars of prepared fruits and vegetables which are heated in preparation.

20 A further object of the invention is to provide a jar lifter which is adaptable to jars of various heights found in household use.

A further object of the invention is to 25 provide a jar lifter whose containing elements are so positioned that they will hold the smallest jar used in preserving edibles.

A further object of the invention is to 30 provide a jar lifter that is simple to construct, efficient in operation, and that is so constructed that the complete space within the lifter may be utilized for the work intended, and thus by utilizing the complete device will require no excess material in its 35 construction.

With these and other objects in view reference is had to the accompanying drawing in which—

Fig. 1 is a side elevation of the device in 40 the process of application;

Fig. 2 is a side elevation of the device showing its application to various sizes of jars;

Fig. 3 is a sectional view on the line 3—3 45 of Fig. 2 showing blades in plan; and

Fig. 4 is a side elevation of the handles and shows method of utilizing handle space.

Having reference to the drawings like numerals refer to like parts through the several figures and the numeral 1 refers to the outer handle and 2 to the inner handle, each being rigidly attached to the top bands 3 and 4 respectively in any suitable manner, in this case by the rivets 5.

55 The top bands are hinged together by the rivets 6 and are formed semi-circular so

that when hinged together they form a complete circle, the circle being of a diameter to receive the largest jar.

The bands are brought low by extending 60 the handles, see Fig. 4, which provides a relatively high handle wherewith to accommodate a tall jar, and positions the bands low enough to embrace the next tallest jar at the shoulder 7, as shown in Fig. 2. This 65 construction prevents the two tallest jars from tipping, which might occur from the relatively heavy weight, and still permits the design of the invention to be such that it will be very little higher than the tallest 70 jar.

Attached to the bands are uprights 8 and 9 and these carry the blades 10 and 11 respectively which will be presently explained.

75 The uprights consist of two pair, one pair being rigidly attached to, or made a part of, each semi-circular band. The four uprights are spaced equally so that no space shall be greater than another, and the uprights have 80 a width that will reduce the size of the space so that the smallest jar cannot escape through. This is shown in Fig. 3, where the dotted lines represent the diameter of the small jar 12 and shows the relative size 85 of the jar as compared with the spaces.

Obviously this manner of spacing the uprights requires that they be attached to the upper band at a distance back from the hinge 6. This makes a continuous circular 90 band possible, which when joined together laterally by means of the handles, eliminates the necessity of a cross tie from hinge to hinge to prevent the parts spreading.

The blades 10 and 11 are made of thin 95 material to readily slip under the rounded edge 13 of the jar 14 and are attached to the uprights in any suitable manner preference being given however to the form shown which consists of upturned ends 15 100 riveted to the uprights, with the blades positioned at right angles thereto as this form and positioning provides ample supports to the uprights.

For further strengthening and as a guide 105 to the jars lower bands 16 are provided which are rigidly attached to the uprights and adjacent to the blades.

In use the handles are opened thus opening the jaw, which is formed of the blades 110 and uprights, until wide enough to receive the jar when the device is pressed down-

ward to the bottom of the jar; the handles are then closed forcing the blades under the jar which will safely support the jar while it is raised and deposited.

5 Having thus described my invention, I claim—

1. In a jar lifter, a pair of curved handles, a pair of semi-circular top bands having their ends hinged together to form a complete circle, each of said top bands mounting one of said handles, a pair of uprights rigidly attached to each of said top bands, at a distance back from said hinges, a pair of blades rigidly attached one to each pair 10 of uprights, at right angles thereto, and a pair of lower bands rigidly attached one

to each of said uprights, and adjacent to said blades.

2. In a jar lifter, the combination of a pair of handles, a pair of semi-circular top bands, having their ends hinged together and forming a complete circle, each of said top bands rigidly mounting one of said handles, a pair of uprights rigidly attached to each of said top bands, and spaced equidistant with its fellows about said top bands, a pair of blades, one of which is attached to each pair of uprights, at right angles thereto, and a pair of lower bands, one of which is attached to each pair of uprights. 25 30

In testimony whereof I affix my signature.

JOSEPH E. RINGEL.
